CORK RETAINER FOR VACUUM BOTTLES
AND THE LIKE

Joseph Henry Herrmann, Oakland, Calif.

Application November 7, 1934, Serial No. 751,842

5 Claims. (Cl. 215—83)

The invention relates to devices used in connection with a vacuum or thermostatic bottle or the like for maintaining the cork or other closure for the bottle in seated closed position when the bottle parts are operatively assembled.

Considerable difficulty has been encountered in providing a closure for vessels such as a vacuum bottle which will remain tightly sealed in the vessel when the same is subjected to jars or vibrations. As will be understood, any loosening of the closure in a thermal type of bottle is of more than usual importance by reason of the use of the bottle for preserving the contents therein in a hot or a cold condition for long periods of time and any slight loosening of the closure permits a thermal communication of the contents with the exterior of the bottle. A principal object of my invention therefore is to provide a means for positively retaining the cork or similar closure of vacuum bottles and the like against loosening from a tightly sealed closure position in the bottle.

In carrying out my invention, I prefer to utilize the usual threaded cup shaped cap provided on the vacuum bottle or the like as a support for my cork retaining device and as an important feature of my invention, I provide for a swivel engagement between the cap and cork retaining means so as to permit free and unrestricted turning of the cap to secure the same in position or to remove the same from the bottle without incurring any frictional or abrasive action between the means and cap.

A further object of my invention is to provide a device of the character described which will have a simplified and improved type of connection between the cork closure for the bottle and the means for retaining the cork in closed position.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

50 Referring to said drawing:

Figure 1 is a fragmentary side elevation of a vacuum bottle having the end thereof broken away and shown in section to illustrate the closure retaining means of my invention.

55 Figure 2 is a fragmentary cross sectional view

of the vacuum bottle shown in Figure 1 and is taken substantially on the plane of the line 2—2 of Figure 1.

Figures 3, 4 and 5 are plan views of one of the parts of the retainer assembly and illustrates the successive bending of portions of the member to obtain the same in its final arrangement.

Figure 6 is an exploded perspective view of the closure retainer means.

Referring more particularly to the drawing, 10 the means 7 of my invention is here shown in combination with a vacuum bottle 8 having a cork closure 9 arranged for insertion into the open neck 10 of the bottle and provided with the usual inverted cup shaped cap 11 which is 15 arranged for positioning over the top of the bottle and for threaded connection with the outer side thereof. In the present arrangement, the means 7 comprises, in part, a helical spring 12 which is arranged to be pressed from the under side 13 20 of the cap 11 against the top 14 of the cork 9.

As an important feature of my arrangement, I have provided for a means of connection between the spring 12 and the under side 13 of the cap which while supporting and urging the 25 spring in the direction of the cork, at the same time permits of a free relative rotation between the cap member and spring without incurring any abrasive action against the under side 13 of the cap. As here shown, the immediate contact between the cap and the spring is afforded by a disc member 16 which has a swivel connection with the top of the spring 12. As may be best seen from Figures 1 and 2, the disc 16 is provided with a depressed perforated center portion 17 which carries in countersunk relation to the upper surface thereof a rivet 18 which extends through the disc to the under side thereof and engages therewith the upper end of the spring 12 which for the purpose of such engagement is 40 preferably reduced in diameter towards the upper end thereof. Thus while the rivet 18 prevents the disc member and spring against endwise loosening, the same provides for free rotation of the disc relative to the spring 12 and 45 together with the under side 13 of the cap.

On the other hand, the opposite end 21 of the spring is fixedly secured to the cork 9 and held against relative rotation thereto and is associated therewith generally as an effective one piece 50 unit. The means for so associating the spring and cork here comprises an anchor plate 22 for securing to the spring and which is fixedly held on the top 14 of the cork by means of a screw 23. As may be best seen from Figures 3 to 6, 55

the anchor plate is provided with lugs 25 for engaging over the lower coil of the spring and clamping the same to the plate and is further formed with a transverse fold 24 which serves to draw together opposed portions 26 of the lugs for entry thereof into side grooves 27 formed in the head 28 of the screw. In accordance with the present arrangement, the plate 22 may be formed from a blank of sheet metal as shown in Figure 3 by a process which first involves bending the lugs 25 from a center portion of the blank into superimposed position thereover, and then pressing the fold 24 from the sides of the blank so as to draw the inner folded extremities 15 of the lugs together and into the screw slots aforesaid. As will be noted from these figures, the center portion of the blank is relatively open so as to space the folds 24 a distance sufficient to straddle the lower end 21 of the spring and to in this manner serve to center the spring over the head 28 of the screw.

I claim:

1. For use with a vacuum bottle or the like having an open end and a cork arranged for seating in said end and a cap arranged for mounting on said bottle and enclosing in spaced relation said end and cork, a spring arranged to be compressed between said cap and cork for pressing the latter into its seat, a disc shaped member engaging between said spring and cap, and a rivet rotatably carried by said disc member and secured to said spring.
2. For use with a vacuum bottle or the like having an open end and a cork arranged for seating in said end and a cap arranged for mounting on said bottle in spaced relation over said end and cork, a spring arranged to be compressed between said cap and cork for pressing the latter into its seat, a disc shaped member engaging between said spring and cap and provided with a depressed perforated center portion, and a rivet countersunk in said portion and rotatably carried by said disc member and secured to said spring.
3. For use with a vacuum bottle or the like having an open end and a cork arranged for

seating in said end and a cap arranged for enclosing in spaced relation said end and cork, a spring arranged for mounting between said cap and cork for urging the latter to a seated position, means for securing said spring to said cork comprising, a plate provided with a pair of lugs arranged for engaging the end of said spring, a screw mounted in said cork and provided with a slotted head, and folds formed in said plate for drawing portions of said lugs into the slots in 10 said head.

4. For use with a vacuum bottle or the like having an open end and a cork arranged for seating in said end and a cap arranged for enclosing in spaced relation said end and cork, a 15 helical spring arranged for mounting between said cap and cork for urging the latter to a seated position in said end, means for securing said spring to said cork comprising, a plate formed with an open center portion and provided with a pair of lugs on opposite sides of said open portion arranged for engaging over the end coil of said spring, a screw mounted in said cork and provided with a slotted head, and folds formed in said plate for drawing portions of 25 said lugs into the slots in said head.

5. For use with a vacuum bottle or the like having an open end and a cork arranged for seating in said end and a cap arranged for enclosing in spaced relation said end and cork, a 30 helical spring arranged for mounting between said cap and cork for urging the latter to a seated position in said end, means for securing said spring to said cork comprising, a plate formed with an open center portion and provided with a pair of lugs on opposite sides of 35 said open portion arranged for engaging over the end coil of said spring, a screw mounted in said cork and provided with a slotted head, and folds formed in said plate at opposite sides of 40 said center portion for drawing portions of said lugs into the slots in said head, and said folds being spaced to straddle and center the end of said spring.

JOSEPH HENRY HERRMANN. 45
